UNITED STATES PATENT OFFICE.

PHILIP AVILLA, OF SAN FRANCISCO, CALIFORNIA.

INTERNAL-COMBUSTION ENGINE.

1,270,585.

Specification of Letters Patent. Patented June 25, 1918.

Application filed December 26, 1916. Serial No. 138,767.

To all whom it may concern:

Be it known that I, PHILIP AVILLA, a citizen of the United States, residing at the city and county of San Francisco and State of California, have invented new and useful Improvements in Internal-Combustion Engines, of which the following is a specification.

My invention relates to internal combustion engines, and especially to that class known as two-cycle engines, in which an explosive charge is inhaled, compressed, ignited and exhausted at each revolution of the crank shaft.

10 It consists of a hollow piston reciprocated within a working cylinder, a second piston reciprocable within the first, a crank shaft and connecting rod through which power is transmitted by the action of one 20 piston, a cam and rocker arm connection with the other piston, and intermeshing gear wheels by which the movements of the two pistons are made relative.

It also comprises details of construction 25 which will be more fully explained by reference to the accompanying drawings, in which—

Figures 1, 2, 3, 4 and 5 are each vertical sections, showing the pistons in different positions during a cycle and showing the connections.

As herein shown, A is a cylinder and B is a case upon which it is supported. Within this case is journaled a crank shaft 2 and a 35 parallel shaft 3, each of which has fixed upon it an equal sized gear wheel 4 and 4^a. These gears intermesh so that they will turn together and equally. Within the cylinder A is fitted to reciprocate a tubular piston 6, and within this piston is fitted a second piston 7. The inner piston is connected by a 40 rod 8 with a crank pin 9 upon the disk 4, and the outer piston has an extension lug 10 which is connected by a link 11 with one end 45 of a lever arm 12, the other end of which is pivoted and fulcrumed upon a pin 13 at the opposite side of the case B; and intermediate of the two ends is a roller or pin 14 which fits in a cam-shaped groove 15 formed 50 in the face of the disk 4^a.

With this construction, it will be seen that as the disks are geared together, when in motion, the crank pin on the disk 4 will be revolved in unison with the reciprocations 55 of the piston 7, while the piston 6 will have

a movement of variable speed, caused by the action of the cam 15 through the lever 12.

The operation of the engine will be as follows: The movements of the two pistons from the top, (one being acted on by the crank 9 and the other by the cam 15), will, when both are at the bottom, uncover the inlet passage 16 through which a charge of gas is admitted. The continued movement of the disks causes the abrupt curvature of the cam 15 to act through the lever arm 12, so as to force the piston 6 up to the end of the cylinder, while regular crank motion conveyed by the crank 9 will impel the inner piston 7 more slowly, thus causing a separation of the pistons during the up stroke.

A transfer port 20 connects the upper end of the cylinder with the space between the pistons, so that as the piston 7 moves upward 75 the piston 6 will have arrived near the top and the gas will be transferred from the upper part of the cylinder to the space between the pistons, and afterward by the final following movement of the piston 7, the 80 transfer ports being closed, the gas will be compressed between the pistons. When the piston 7 has completed the up stroke and the compression of the gas is effected, an ignition device 18 is energized and the charge 85 is exploded. This explosion takes place when the crank 9 is passing the upper center and causes the piston 7 to move down to the end of the stroke, the piston 6 remaining at the upper end of the cylinder until 90 the revolution of the disk 4 has brought the cam 5 into position to act upon the piston 6 and move it down with greater speed. At this time the exhaust port 19 has been uncovered by the piston 7 and the downward 95 movement of the piston 6 will expel the waste product successively through the ports 17 as they register with the exhaust port 19.

The position of the crank and cam are then relatively such that the pistons are contiguous at the lower end of the stroke, and further movement causes them to again move upward to compress another charge which is admitted through the inlet port 16 above the piston 6 during the time in which the pistons 105 are at the lower end of their stroke and while the crank is passing around its lower arc of curvature.

Fig. 5 shows the piston at the top of its stroke, the ports 20 and 17 connecting with 110

the space between the pistons which admits the gas from above the piston 6 to receive its final compression between the pistons by the completion of the upward stroke of the 5 piston 7. As soon as the crank 9 passes the upper center ignition takes place through the spark plug 18 and this acts to force piston 7 down. The gear 4 acts to turn the gear 4^a and through the cam 15 and arm 12 10 causes the piston 6 to follow and expel the products of combustion through the port 19. The small amount of gas which may remain above the piston 6 will also escape and the two pistons will be brought together 15 again at the bottom of the stroke with the inlet passage 16 admitting a new charge of mixture into the cylinder A above the piston 6.

Having thus described my invention, what 20 I claim and desire to secure by Letters Patent is—

1. In an internal combustion engine, a cylinder having a transfer port in its side wall adjacent its head, a spark in the port, 25 a tubular outer piston reciprocal in the cylinder and provided with a solid head having a pocket in its outer face opposing the cylinder head, said piston also having a port through its side and disposed in such proximity to the piston head as to permit communication through the transfer port with the space between the heads of the cylinder and piston as the latter approaches its inward limit of movement, communication 30 with said piston pocket being shut off when the piston is at its inward limit of movement whereby the gases confined within the 35 piston pocket may serve as a cushion for

the piston, an inner piston reciprocal in the outer piston, means for operating the piston, and an inlet and an outlet in the cylinder. 40

2. In an internal combustion engine, a cylinder having a transfer port in its side wall adjacent its head, a spark in the port, 45 a tubular outer piston reciprocal in the cylinder and provided with a solid head having a pocket in its outer face opposing the cylinder, said piston also having a longitudinal series of ports through its side, the 50 innermost port being disposed in such proximity to the piston head as to permit communication through the transfer port with the space between the heads of the cylinder and piston as the latter approaches its inward limit of movement, communication 55 with said piston pocket being shut off when the piston is at its inward limit of movement whereby the gases confined within the piston pocket may serve as a cushion for the 60 piston, an outlet in the cylinder over which the outermost piston port moves when the piston is at its inward limit of travel, an inner piston reciprocal in the outer piston to uncover the outermost port thereof, means 65 connecting the pistons for timed movement, and an inlet for the cylinder opened and closed by the outer piston.

In testimony whereof I have hereunto set my hand in the presence of two subscribing 70 witnesses.

PHILIP AVILLA.
